BOUQUET HOLDER

Gene R. Meyer, P.O. Box 7, Deer Park, N.Y. 11729

Filed May 7, 1971, Ser. No. 141,466

Term of patent 14 years

Int. Cl. D11—02

U.S. Cl. D35—3 R

FIG.1.

FIG.2.

FIG.3.

FIG.4.

FIG. 1 is a perspective view of a bouquet holder showing my new design;

FIG. 2 is a slightly enlarged front elevational view thereof;

FIG. 3 is a similarly enlarged rear elevational view; and

FIG. 4 is a side elevational view.

I claim:

The ornamental design for a bouquet holder, substantially as shown and described.
